UNITED STATES PATENT OFFICE.

WILLIAM B. EICK, OF ROCHESTER, NEW YORK, ASSIGNOR TO GENESEE CUT GLASS COMPANY, OF ROCHESTER, NEW YORK, A CORPORATION OF NEW YORK.

DESIGN FOR A CUT-GLASS ARTICLE.

45,087.

Specification for Design.

Patented Dec. 30, 1913.

Application filed February 7, 1913. Serial No. 746,956. Term of patent 3½ years.

To all whom it may concern:

Be it known that I, WILLIAM B. EICK, a citizen of the United States, residing at Rochester, in the county of Monroe and State of New York, have invented a new, original, and ornamental Design for Cut-Glass Articles, of which the following is a specification, reference being had to the accompanying drawings, forming part thereof.

The drawings show the design as applied to a convex surface, Figure 1 being a face-view or a view from a direction normal to the surface, while Fig. 2 is a view in a direction substantially parallel to the portion

of the surface upon which the design is employed.

The design resides in the flower-like figure shown in the drawings, this figure being produced by straight cuts in the surface of the glass and being applicable to glass articles of various forms.

I claim:

The ornamental design for a cut-glass article as shown and described.

WILLIAM B. EICK.
